(57) **CLAIM**

The ornamental design for a quick release nut for a bicycle hub, as shown and described.

DESCRIPTION

FIG. 1 is a perspective view of a quick release nut for a bicycle hub in accordance with my new design;

FIG. 2 is a first side elevational view of the quick release nut in accordance with my new design;

FIG. 3 is a second side elevational view of the quick release nut in accordance with my new design;

FIG. 4 is a top plan view of the quick release nut in accordance with my new design;

FIG. 5 is a bottom plan view of the quick release nut in accordance with my new design;

FIG. 6 is a first end elevational view of the quick release nut in accordance with my new design; and,

FIG. 7 is a second end elevational view of the quick release nut in accordance with my new design.
